UNITED STATES PATENT OFFICE.

GEORGE L. TYLER, OF LYNN, MASSACHUSETTS.

LEATHER-SPLITTING MACHINE.

SPECIFICATION forming part of Letters Patent No. 319,357, dated June 2, 1885.

Application filed September 3, 1883. (No model.)

To all whom it may concern:

Be it known that I, GEORGE L. TYLER, of Lynn, in the county of Essex and Commonwealth of Massachusetts, have invented certain new and useful Improvements in Leather-Splitting Machines, of which the following, taken in connection with the accompanying drawings, is a specification.

Figure 1 of the drawings shows my invention in perspective. Fig. 2 is the same as Fig. 1, except the top back roll, which is here represented as thrown upward and backward on its supporting-arm. (In this figure the front of the machine is the right hand of the figure.) Fig. 3 is a transverse vertical section cut through the feed-rolls, and represents the right-hand end of the machine when viewing Fig. 1. The cutting-plane in making this view is supposed to pass through the machine on dotted line $x\ x$, indicated in Fig. 4. Fig. 4 is a longitudinal vertical section cut through the machine on dotted line $y\ y$, as indicated in Fig. 3, and illustrates the position of the trimming-knife relatively to the feeding-rolls. Figs. 5 and 6 illustrate the mechanism for holding and adjusting the edge-trimming knife.

This invention is an improvement to be applied to the machine described and shown in Letters Patent of the United States granted to me, dated May 24, 1881, numbered 242,079, and entitled "Machine for Splitting Leather," and further shown and described in Letters Patent of the United States granted to me, dated the 7th day of February, 1882, numbered 253,449, and entitled "Leather-Splitting Machine," to which Letters Patent reference may be had.

By reference to the above-mentioned Letters Patent it will be readily understood that the object of this series of inventions is to effect a saving of leather. This is done by taking a piece of the leather, which may be so small as to be ordinarily useless, and first trim it to a straight line on one edge, and then split it through the center longitudinally, except a little line along the straight edge, where it is left united, and then opening out the two halves made by so splitting the piece, and as a result produce one piece hinged together at the center and having twice the surface and half the thickness of the original

piece. Heretofore it has been customary to cut the piece straight on one side before subjecting it to the machine; but to effect this result automatically while passing it through the machine is the object of this last improvement in said machine.

This present invention consists in a trimming-knife so arranged in reference to the feed-rolls and splitting-knife described in the Letters Patent above referred to, and also in reference to the additional rolls to be described hereinafter, as to cause a piece of leather in passing through the machine to be automatically trimmed thereby to a straight line on one edge before being subjected to the operation of splitting the same longitudinally, as referred to in the patents above mentioned.

The invention also relates to improvements in the feeding and guiding mechanism involving matters of construction, more fully described hereinafter, and specifically pointed out in the claims.

I shall not repeat here the description of those parts of the machine which have already been fully explained in the Letters Patent above referred to, since the additional features herein presented have been added to the machine as there described without having made any material change in the arrangement of those parts or in the manner of working the same.

Directly in front of the feed-rolls A A, as represented in the above-named Letters Patent No. 253,449, I have arranged two additional rolls, B B. (See Fig. 1.) Said rolls B B are provided with suitable gearing, which is arranged at the left side of the machine, as represented, and which operates the rolls, so as to cause the contiguous surfaces thereof to move in the same direction toward the rolls A A in an obvious manner. The top roll, B, is journaled in the pivoted arm a , which permits being turned up, as represented in Fig. 2. The top roll, B, when put down, as represented in Fig. 1, is held in contact with the bottom roll by means of the pin b , which passes down through a hole in the end of the supporting-arms a , and out through the bottom of the machine. It is held in position by means of a nut on the end thereof, while a spring, arranged in an obvious manner between the head of the pin b and the end of the arm a , permits the roll to yield up-

ward and automatically adjust itself to the different thicknesses of the leather chips, and so to facilitate the operation of passing the leather through the rolls.

- 5 The rolls B B are arranged relatively to the rolls A A, so that a piece of leather, in departing from the rolls B B, is taken in by the rolls A A and carried thereby directly to the splitting-knife f.
- 10 At the end of the rolls B B is arranged the trimming-knife 2. The cutting-edge of this knife bears against the ends of the rolls, and slightly in rear of the vertical line which passes through the centers of the rolls. (See Fig. 3.) The back of the knife rests against the end of the guard-plate 3, and the inner side of the knife is in the same plane with the inner side of the guard-plate 3, and so connected forms with the plate 3 a guard leading 15 from the cutting-edge of the knife 2 to the rear end of the splitting-knife f. The distance between this guard and the side of the knife f determines the amount of leather left unsplit along the straight edge of the piece, as more 20 fully described in the Letters Patent referred to above.

From the foregoing it will be understood that a piece of leather is first fed into the rolls B B, and is carried thereby onto the knife 2, which 25 trims the edge of the leather, leaving the piece which passes through the rolls nearly or quite straight on one edge. It is then directly taken up by the rolls A A, (its straight edge being always in contact with the guard 3,) and 30 is carried forward by the rolls A A onto the splitting-knife f, whereby the leather is split nearly or quite through the center longitudinally, as more fully explained in the Letters Patent above referred to. It is then opened 35 out and ready for use.

When a piece of leather is placed between the feed-rolls B B it is of course important that the straightened edge thereof, as it leaves the cutting-edge of the knife 2, should press 40 closely against the side of the knife and the guard 3 while it passes through the machine. This operation is effected by the peculiar shape of the feed-rolls A A and B B, which are formed with unequal diameters, the largest 45 diameter being at the right-hand end, Fig. 2, and gradually diminished till the shortest diameter is reached at the opposite end. This conical form of the rolls, though but little, tends to press the leather closely up against 50 the knife and guard, as described. The plate e, arranged as shown in Fig. 3, prevents the pieces from falling down between the two sets of rolls, while a suitable table or plate, h, is arranged at the front of the machine, on 55 which the pieces may be laid before being passed to the rolls, all of which is plainly useful, though not absolutely indispensable.

Figs. 5 and 6 are detached sectional views illustrating the trimming-knife 2 and its adjusting mechanism. Said mechanism consists of the plate 4 and eccentric pins 5 and 6. The plate 4 is clamped against the bottom or bed-plate of the machine by means of the said pins 5 and 6, all arranged as represented in Fig. 5. The pins are provided with cams 65 arranged to operate in suitable holes in the plate, as seen in Fig. 6. The trimming-knife 2 is extended through a slot in the end of the plate 4, as represented. By reference to Fig. 2 it will be observed that the knife is fitted 70 in a suitable niche formed by cutting into the corner of the guard 3. This is brought about by clamping the plate 4 to the bottom of the machine-table in such position as to allow the knife 2 to extend upward at the 75 end of the rolls B B, and in close proximity to the said guard 3. The eccentric pins 5 and 6 are then operated to press the knife into the niche in the guard 3 and firmly clamp it against the same, as represented. This 80 method of clamping the knife against the guard gives great strength and stability thereto, and 85 enables it to enter the very hardest leather without danger of breaking.

I claim—

1. In combination, in a machine for splitting leather, rolls A B, a splitting-knife parallel with the axis of said rolls, and an edge-trimming knife and suitable guide, said knife and guide being set in the manner described, 90 whereby a part of the leather on the trimmed edge is left unsplit, substantially as described.

2. In combination with a leather-splitting machine, the rolls A B, the splitting-knife f and the trimming-knife 2, with suitable guides, 95 the knives and guides being arranged in relation to each other, as described, whereby the splitting-knife cuts within the line of the trimming-knife and leaves an uncut edge, substantially as described.

3. The combination, in a leather-splitting machine, of the feeding-rolls A A and B B, made of slight conical form, the guard-plate 3 and cutting-knife 2 in the described relation to the feeding-rolls, and the cutting-instrument f, all 100 substantially as described.

4. In combination with the guard 3, the plate 4, slotted at one end to receive the knife 2, the said plate being secured to the bottom plate of the machine by the eccentric pins 5 and 6, whereby it is adapted to clamp the knife 2 in position, substantially as described.

Signed in presence of two witnesses.

GEO. L. TYLER.
